Attorney

UNITED STATES PATENT OFFICE

HENRY B. IVEY, OF GOLDSBORO, NORTH CAROLINA

CIGAR AND CIGARETTE LIGHTER

Application filed September 4, 1929. Serial No. 390,295.

This invention relates to lighters, and has more particular reference to a cigar and cigarette lighter.

The primary object of this invention is to provide a simple and inexpensive cigar or cigarette lighter which may be readily carried about ones person, will be handy to manipulate, and at the same time present a neat and attractive appearance.

10 A still further object of the invention is to provide a lighter of the character above mentioned, including a casing, the same being in simulation to a watch casing, and having arranged therein in a neat, compact manner, a fluid reservoir, a wick extending from the reservoir, and a neat, handy and easy operable sparking device for igniting the wick.

Other objects and advantages of the invention will become apparent during a study of the following description, taken in connection with the accompanying drawings, wherein:

Figure 1 is a plan view of the lighter, the casing of the lighter being shown in open position.

Figure 2 is a detail vertical transverse sectional view taken substantially on line 2—2 of Figure 1.

30 Figure 3 is a detail sectional view taken substantially on line 3—3 of Figure 1.

With reference more in detail to the drawings, it will be seen that my improved lighter comprises a somewhat circular casing 5 having a lid 6 hingedly connected thereto through the medium of spring hinge 7. The lid is normally maintained closed through the medium of the usual or conventional spring snap 8. The casing is further provided with the swivelly mounted loop 9 to facilitate the attachment of a chain to the casing, all of which construction is conventional, especially in watch cases, and a more detailed description thereof is deemed unnecessary.

It is to be noted that the casing 5 and lid 6 are of preferably concavo-convex configuration being in such details and almost exact replica of a watch casing.

50 The casing 5 is provided with a partition

10, while arranged within the casing 5 beneath the partition 10 is a fuel reservoir 11 which is open at its top, said top being in registration with a suitable circular opening 12 formed in the partition 10. A circular 55 cover plate 13 is disposed over the opening and is maintained in closed position through the medium of set screws 14.

Of course, the fluid within the container may be any desired fluid used in such lighters. 60 The cover 13 is provided with a suitable opening through which one end of a wick 14 extends, the major portion of the wick being submerged in the fluid of the container 11 as is the usual practice. 65

Supported on the partition 10 adjacent the wick 14 is a cylindrical flint holder 15, secured on the partition as at 16. The body of the holder has a horizontal bore extending therethrough from one end to the other, and 70 slidable in this bore is the flint 17 or similar pyrophoric element. An angular spring 18 has one end anchored to the partition 10 rearwardly and to one side of the holder 15 as at 19, and the opposite end of this spring 75 extends into the bore of the container 11, pressing against one end of the flint or pyrophoric elements 17 normally urging the flint outwardly of the container 13 as best shown to advantage in Figure 3. 80

To the other side of the wick 14 directly opposite to the holder 15 there is located on the partition 10 a housing 20. The housing 20 has that end adjacent the flint 17 opened, while the rear wall of the housing is provided with a suitable slot 21. A spark wheel 22 is pivoted within the housing as at 23 a portion of the wheel extending through the open end of the housing as shown to advantage in Figure 1. 85

The spark wheel 22 has formed integral therewith a shank or actuating stem 24, the outer end of which extends through the slot 21 and terminates in a curved handle 25. 90 Normally urging the stem 24 against one end of the slot 21 is a suitable spring 26, the free end portion of which bears against the stem at the junction of the stem and wheel 22, the other end of the spring 26 being anchored 100

within the housing 20, as is also shown to advantage in Figure 1.

The spark wheel 22 is normally maintained in that position shown to advantage in Figure 1 through the action of the spring 26 and the outer end of the flint 17 is maintained in engagement with the teeth of the spark wheel through the medium of the spring 18 as is obvious.

Obviously, by placing one thumb against the handle 25 of the stem 24 and pressing against the same against the action of the spring 26, the spark wheel 22 will be rotated on its pivot, then by releasing, or removing the finger from the handle 25, the spark wheel will be rotated in an opposite direction by the action of the spring 26, and being in contact with the flint 17, will cause a spark for igniting the outer end of the saturated wick 14, as is apparent.

In order to extinguish the wick merely by the action of the closing of the lid 6, there is provided on the lid a tube 27, which tube is open at its lower end, so that when the lid is closed down for closing the casing, the tube 27 will fit over the extending end of the wick 14 as shown to advantage in Figure 2, thus extinguishing the flame, and at the same time preventing the escape of fumes from the casing when one is carrying the lighter about upon the person.

Manifestly, as when opening a watch casing, one need only press on the snap catch 8, thus releasing the cover, the same springing to an open position through the medium of a spring hinge 7, whereby ready access is had to the sparking apparatus for igniting the wick so that one may light a cigarette or cigar as the case may be.

Obviously, the casing may be suspended from a chain such as a watch chain, and the entire casing and contents placed within ones pocket to be carried about in a neat and readily accessible manner.

It is believed that due to the simplicity of the device, a clear understanding of the construction, operation, utility and advantages of a lighter of this nature will be clear to those sufficiently skilled in this art, and a more detailed description is believed unnecessary.

Even though I have herein shown and described the preferred embodiment of my invention, it is to be understood that the same is susceptible to changes fully comprehended by the spirit of the invention as herein described, and the scope of the appended claim.

Having thus described, my invention, what I wish to claim is:

A lighter for the purpose specified comprising a circular casing, a horizontally disposed partition arranged in the casing, said partition provided with a relatively large opening, a fluid reservoir arranged in said

casing and having its open upper end in registry with the opening in said partition, a cover plate on said partition substantially closing said opening, said cover plate provided with a wick accommodating aperture, a wick extending upwardly from said reservoir through said aperture, and means arranged in said casing on said partition for igniting said wick.

In testimony whereof I affix my signature.

HENRY B. IVEY.
